COMBINED ELECTRON DISCHARGE TUBE AND MAGNET

John E. Finn, Plainview, N.J., assignor to North American Philips Co., Inc., New York, N.Y., a corporation of Delaware

Filed Feb. 14, 1967, Ser. No. 5,813

Term of patent 14 years

(Cl. D26—8)

FIG. 1 is a right front perspective view; and
FIG. 2 is a left rear perspective view of a combined
electron discharge tube and magnet.

I claim:

The ornamental design for a combined electron discharge tube and magnet, as shown and described.
